IMPULSE-PUMP.

1,092,873.

Specification of Letters Patent. Patented Apr. 14, 1914.

Application filed May 3, 1913. Serial No. 765,262.

To all whom it may concern:

Be it known that I, WILLIAM H. STUTTZ, a citizen of the United States, and a resident of Toledo, in the county of Lucas and State of Ohio, have invented a certain new and useful Impulse-Pump; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to impulse pumps for use in connection with internal combustion engines for inflating automobile tires, or the like.

The object of my invention is the provision in a pump of the character described, 20 of simple and inexpensive means for frictionally or otherwise acting on some part of the pump pistons for retarding the initial compressing movements of the pump pistons upon an out or compression stroke of the associated engine cylinder piston, whereby the efficiency of the pump is very materially enhanced, as hereinafter fully described.

30 The invention is fully described in the following specification, and while, in its broader aspect, it is capable of embodiment in numerous forms, a preferred embodiment thereof is illustrated in the accompanying drawings, in which the pump and a portion of the engine cylinder to which it is attached are shown in central longitudinal section.

Referring to the drawings, 1 and 2 designate what may be termed the "power" and 35 "compression" cylinders, respectively, of a pump. In the particular pump illustrated the latter cylinder is smaller in diameter and having its bore in longitudinal register with the bore of the other cylinder, as shown.

5 The cylinder 1 is provided at its lower end, in the present instance, with an extension 3, forming an inlet passage 4 to the interior of the cylinder, and this extension has a nipple or connecting member 5 for threading 40 into the spark plug opening or other suitable opening in the compression end of an engine cylinder 6. The outer end of the cylinder 2 is provided with the customary outlet passage 7 in which is disposed an out-

wardly opening valve 8 of any suitable form.

Pistons 9 and 10 are mounted within the cylinders 1 and 2, respectively, for working therein and are rigidly connected by a stem 11 to cause the pistons to move in unison. 60 A passage 12 is provided lengthwise through the stem 11 and the pistons 9 and 10 to open communication between the inlet passage 4 and the compression cylinder 2 of the pump. A valve 13, in the present instance of the ball 65 type, is disposed in the passage 12 and is adapted to seat under back pressure from within the cylinder 2. An inwardly opening breather-valve 14 is carried by the stem 11 and adapted to normally close an opening 15 from the stem passage 12 into the interior of the cylinder 1 above its piston whereby air may be drawn from the atmosphere through inlet openings 16 in the end 70 portion of the cylinder 1, adjacent to the cylinder 2, into the cylinder 1 and thence through the opening 15, passage 12 and into the engine cylinder upon the down or suction stroke of the engine piston. While the breather-valve is shown as being carried by 75 the stem 11 it is not restricted to use in such connection but may be provided in any other suitable part of the pump, as desired.

It is found in practice in the use of pumps of this character that the connected pistons 85 9 and 10 begin to move outward very shortly after the associated engine piston begins its out or compression stroke, so that when the air, which has been forced into the cylinder 2 through the passage 11 from the engine 90 cylinder, has compressed sufficiently in such cylinder to seat the valve 13 in its passage, the small compressing piston 10 will have moved for a considerable portion of its stroke so that it will only act during the remaining portion of such stroke to effect a 95 further compression of the air within the cylinder 2, thus limiting the effective compressing action thereof.

In order to render the pump more efficient in its action I provide an extension or teat 17 on the piston 9 for fitting into the inlet passage 4 when the piston is at or near the limit of its downstroke, the passage 4 forms a socket in which the teat 17 fits so 100 as to form a frictional retaining means whereby the pistons are held or engaged until the pressure produced by the engine

is sufficient to cause disengagement. The extension or teat 17 forms a continuation of the passage 12 through the pump pistons and their connection 11. When the teat 17 is within the passage or socket 4 it co-acts with the passage or socket 4 by reason of its close fitting therein which causes an engagement between the extension or teat 17. This frictionally holds the pistons down until the pressure of the air is raised by the piston of the engine. The air will leak by the teat and enter the space formed beneath the lower piston. When the pressure beneath the lower piston has been raised sufficiently it will cause disengagement between the wall of the socket 4 and the teat 17. The teat 17 may be further engaged by a detent 18 which is carried in the wall of the socket to further aid in the retention of the pistons and yet allow the gradual leakage of the air to beneath the driving piston 9. The detent 18, in the present instance, comprises a ball which works within a socket in the wall of the passage 4 and yieldingly pressed by a spring 19, or any other suitable device, against the outer side wall of the teat 17 when the piston is at the limit of its downstroke as shown in the drawing. The friction resisting the rotation of the ball gives, ordinarily, sufficient additional resistance to hold the pistons temporarily in the operation of the pump and long enough to allow the pressure produced by the engine to rise. The pistons 9 and 10 are retained until the cylinder 20 has been practically filled by air at near the limit of the pressure producible by the engine so that when the pump pistons are released by the pressure which gradually rises beneath the driving piston the pistons will be driven by pressure near the maximum of the pressure producible by the engine, upward to compress the air above the pumping piston. This high pressure on the driving piston being substantially constant gives an increasing momentum to the pistons as they move upward in making their stroke which produces an exceedingly high compression of the air in the pumping cylinder by the impact of the stroke. The pressure producible by the pistons in the pumping cylinder is way in excess to that producible by the mere differential relation between the two pistons.

I wish it understood that my invention is not limited to the locating of the retarding means in any particular portion of the pump, or to any specific construction or arrangement of the parts except in so far as such limitations are specified in the claims.

Having thus described my invention, what I claim as new, and desire to secure by Letters Patent, is,—

1. The combination of a cylinder, a float-

ing pump piston movable in the cylinder, means for permitting air to pass in but one direction to the compression side of the pumping piston, means for pneumatically operating the piston, and an engaging means for holding the said piston at one end of its stroke until the pressure produced by the said pneumatically operating means is sufficient to release the piston which is driven by the said pressure. 75

2. The combination of a pair of connected pistons having a passage way extending therethrough, cylinders surrounding the said pistons, an engaging means for holding the said pistons at one end of their stroke 80 and a means for forcing a fluid through the pistons and to disengage the pistons by the pressure of the fluid on one of the pistons.

3. The combination of a pair of connected pistons, a passageway extending through the 85 said pistons, a pair of cylinders, each piston being located in a cylinder, a teat located on one piston, one cylinder having a socket to frictionally engage the teat with sufficient force to delay the starting of the piston. 90

4. The combination of a pair of connected pistons, one being a driving piston and the other a pumping piston, a passage way extending therethrough, a pair of cylinders, each piston working in a cylinder, a teat located on the driving piston, a socket located in one end of the cylinder surrounding the driving piston to frictionally engage the teat, and means for forcing air through the passage way and beneath the driving piston. 100

5. The combination of a pair of pistons connected together, one being a pumping piston and the other a driving piston, a pair of cylinders, each piston located in a cylinder, a means for permitting air to pass in but one direction to the compression side of the pumping piston, an engaging means for holding said pistons at one end of their stroke and means for forcing a fluid against the compression side of the driving piston to cause disengagement of the pistons when the pressure has been raised by said fluid forcing means. 110

6. The combination of a pair of pistons connected together, one a pumping piston and the other a driving piston, a pair of cylinders, each piston located in a cylinder, the pumping piston having a passage way therethrough and a valve for permitting air to pass in but one direction through the passage way to the compression side of the pumping piston, an engaging means for holding said pistons at one end of their stroke, and means for forcing a fluid into the cylinders and against the compression side of the driving piston to disengage the pistons from the engaging means and give driving momentum to the pumping piston. 120

7. The combination of a pair of connected pistons, a pair of cylinders, each piston lo- 130

cated in a cylinder, one piston being a driving piston and the other piston a pumping piston, means for engaging the pistons to hold them at one end of their stroke and 5 means for raising the pressure on the driving piston to cause disengagement of the pistons from the engaging means and producing an increasing momentum in the pistons during the compression stroke.

10 8. The combination of a pair of connected pistons having a passage way extending therethrough, cylinders surrounding the pistons, one of the pistons being a driving piston and the other a pumping piston, a detent 15 for engaging the pistons when the pistons are at one end of their stroke, means for forcing a fluid through the passage way and causing it to separate the pistons from the detent when the pressure has been raised be- 20 hind the driving piston.

9. The combination of a pair of connected pistons having a passage way extending therethrough, cylinders surrounding the pistons, a breather valve for allowing air to enter the passage way to the compression sides 25 of the pistons, a teat located on one piston, one cylinder having a socket fitting the teat, a detent for engagement of the pistons when the pistons are at one end of their stroke, means for forcing a fluid through the passage way and to leak by the teat to press upon the piston having the teat to disengage the piston.

In testimony whereof, I have hereunto signed my name to this specification in the presence of two subscribing witnesses.

WILLIAM H. STUTTZ.
